CLAIM

The ornamental design for an electrical stimulator and mounting patch, as shown and described.

DESCRIPTION

FIG. 1 is a perspective view of an electrical stimulator and mounting patch according to the present invention.

FIG. 2 is a front elevation view thereof;

FIG. 3 is a rear elevation view thereof;

FIG. 4 is a bottom plan view thereof;

FIG. 5 is a top plan view thereof;

FIG. 6 is a right side elevation view thereof; and,

FIG. 7 is a left side elevation view thereof.

The dash dot lines immediately adjacent to the claimed areas in the views represent the boundaries of the claimed design. The dashed lines in the figures illustrate the portions of the design that form no part of the claimed design. None of the broken lines form any part of the claimed design.
